MINE EXPLoder

Harry T. Woolson, Detroit, Mich., assignor to
 Chrysler Corporation, Highland Park, Mich., a
 corporation of Delaware

Application July 3, 1945, Serial No. 602,972

6 Claims. (Cl. 89—1)

1

This invention relates generally to mine exploders and more particularly to mine exploders for use in connection with vehicles.

In modern military operations, mine fields containing anti-personnel and anti-tank mines are often placed in the path of advancing armies. A path must be cleared through these mine fields to permit the safe movement of tanks and infantry therethrough. One solution to this problem is to equip a tank with a mine exploding device located in front of the tank and having ground-engaging wheels of such size and weight that they will explode any mine over which they pass. Difficulties encountered with mine exploders of this type include lack of maneuverability and the problem of suspending the wheels so that irregular ground areas may be adequately covered and all mines exploded, and the mine blast effectively absorbed without causing serious damage to the mine exploder or the tank.

These disadvantages are effectively overcome by the present invention, in which a plurality of torsion mounted wheels are independently suspended from a frame located in front of the tank, the frame being pivotally connected to a boom extending forwardly from the tank and operating to, in effect, tow the mine exploder from a pivot located in front of the mine exploder and substantially on the longitudinal centerline of the tank.

It is, therefore, an object of the present invention to provide a mine exploder located in front of a vehicle and pivotally connected to a member extending forwardly from the vehicle. A further object is to locate the pivot substantially on the longitudinal centerline of the vehicle and ahead of the axes of mine exploding wheels carried by the mine exploder. This arrangement materially increases the maneuverability of the vehicle when propelling the mine exploder.

Another object of the invention is to provide a mine exploder having ground engaging wheels torsionally suspended from the frame of the mine exploder.

A further object of the invention is to provide a mine exploder having independently mounted ground engaging wheels adapted to follow the terrain and to explode mines over which they pass, and designed to absorb mine blasts without being seriously damaged.

Other objects and advantages of the present invention will be made more apparent as this description proceeds, particularly when considered in connection with the accompanying drawing, in which:

2

Fig. 1 is a side elevation of the mine exploder attached to a military tank;

Fig. 2 is a plan view thereof;

Fig. 3 is a cross-sectional view taken substantially on the plane indicated by the line 3—3 of Fig. 2;

Fig. 4 is a cross-sectional view taken substantially on the plane indicated by the line 4—4 of Fig. 3 through one of the arms, and

Fig. 5 is a cross-sectional view taken substantially on the plane indicated by the line 5—5 of Fig. 2.

Referring now more particularly to the drawings, the reference character 10 indicates a military combat tank having tracks 11, a hull 12, and a turret 13 carrying a gun 14. Extending forwardly from the front of the tank is a boom 15, comprising a pair of converging arms 16 having their forward ends joined by a bracket 17 and their rearward portions pivotally mounted upon stub axles 18 extending from opposite sides of the hull 12 of the tank. A reinforcing member 19 interconnects the arms 16 of the boom.

The arms 16 extend rearwardly of the stub axles 18 and are provided with arcuate slots 20 adapted to engage suitable stops 21 provided on the sides of the hull to limit the pivotal movement of the boom. The boom 15 is thus free to pivot about axles 18 within predetermined limits to enable the mine exploder to traverse rough and rolling terrain.

The forward end of bracket 17 of the boom is provided with a tapered aperture 22 adapted to receive the tapered shank 23 of a ball joint 24. A nut 25 locks the ball joint 24 to bracket 17. The lower portion of the ball joint is formed as a hemispherical ball 26 which is adapted to be received within a complementary shaped socket 27 carried upon the forward edge of the mine exploder frame 28.

Frame 28 extends transversely the entire width of the tank and has front and rear sections 30 and 31 respectively, and side sections 32. The frame 28 may be cast in one piece of armor plate material or may be fabricated as desired.

Bolted to the central portion of the front section 30 of the frame is a bracket 33 having formed integrally therewith the socket 27 previously mentioned. It will readily be apparent that the hemispherical ball 26 carried by the boom and the socket 27 carried by the mine exploder frame cooperate to form a universal coupling permitting universal movement between the boom and frame. Downward movement of frame 28 is limited by means of a pair of flexible cables 34 having op-

posite ends pivotally connected to brackets 35 and 36 provided upon the rear section 31 of the frame and the arms 16 of the boom respectively.

Disposed within the frame 28 are a plurality of transversely spaced independently suspended mine exploding wheels 37 each rotatably mounted in an arm 38 which in turn is pivotally connected to a bracket 39 bolted to the front section 30 of the mine exploder frame by means of bolts 40. The brackets 39 are uniformly spaced across the entire width of the front section 30 of the frame. Inasmuch as the structure for independently suspending each roller 37 is identical, only one will be described in detail.

Each bracket 39 is provided with a circular bore 41 receiving an annular torsion rubber bushing 42 which is suitably bonded to the bracket. Co-axial with aperture 41 and the annular bushing 42 is a hollow stub axle 43 having its outer peripheral surface bonded to the inner surface of the rubber bushing. Thus axle 43 is torsionally mounted within the bracket for pivotal movement.

The arm 38 comprises a pair of side plates 44 spaced apart a predetermined distance and having their rearward ends connected by a cross-member 45. The forward ends of plates 44 have aligned circular apertures 46 engaging the opposite ends of axle 43 and suitably secured thereto, as for example by welding. At substantially their mid-points the side plates 44 are provided with aligned apertures 47 receiving the opposite ends of an axle 48 rotatably mounted therein. The mine exploding wheel 37 is carried by axle 48 intermediate the side plates 44 of arm 38, being spaced therefrom by annular spacers 49.

The forward ends of the side plates 44 of arm 38 are provided with stops 50 adapted to engage the inner surface 51 of the front section 30 of the frame 28 to limit the downward pivotal movement of wheel 37 and arm 38 relative to the frame. Upward pivotal movement of the arm relative to the frame is limited by engagement of member 45 of the arm with a resilient pad 52 carried by the rear section 31 of the frame.

From the foregoing it will be apparent that each wheel-carrying arm 38 is independently pivotally connected to the front section of the mine exploder frame by means of a torsion bushing. The weight of frame 29 and boom 15 are transmitted through the torsion bushings 42 to the ground engaging wheels 37, and since the frame and boom are relatively heavy, it will be seen that each wheel 37 exerts a considerable pressure upon the ground. The mine exploder is designed so that this pressure will be sufficient to explode any mine located in the ground.

Since the wheels 37 are independently suspended each maintains engagement with the ground regardless of the irregularity of the terrain. The frame 28 extends the entire width of the tank and the wheels 37 are positioned close enough together so that all mines in the path of the tank are exploded. All of the exposed parts of the mine exploder, including wheels 37, arms 38, and frame 28, are constructed of armor-plate material and are of sufficient mass and strength to resist the blast of exploding mines without being seriously damaged. The resiliency of the entire mine exploder construction also contributes to the avoidance of damage by effectively absorbing the blast. Another factor contributing to the elimination of damage is the fact that arms 38 are closely adjacent each other and are inclosed by frame 28, thus enabling them to co-

operate with each other and with the frame in resisting the transverse force exerted upon wheels 37 by the blast of an exploding mine.

In addition to proper coverage of irregular terrain by the independent suspension of the wheels 37, the pivotal mounting of boom 15 upon axles 18 permits the entire mine exploder to automatically follow an inclined slope or hill.

The present invention provides maneuverability heretofore unobtainable when mine exploders were attached to tanks or other vehicles. This is accomplished by the universal pivotal connection provided between boom 15 and frame consisting of ball 26 and socket 27. This universal connection is located at the extreme forward edge of the mine exploder and substantially on the longitudinal center line of the tank. A caster effect is thus obtained, permitting the mine exploder frame 28 to pivot freely when the tank is turned. The construction is such that, although the mine exploder is located in front of the tank, it is, in effect, towed by the boom 15. Furthermore, the entire construction is relatively low, providing an unobstructed field of vision for the tank driver.

Although I have shown and described certain embodiments of the invention, it will be understood that I do not wish to be limited to the exact construction shown and described, but that various changes and modifications may be made without departing from the spirit and scope of my invention as defined in the appended claims.

What I claim is:

1. A mine exploder comprising a boom member, means for pivotally mounting said boom member at a rearward portion thereof to a forward part of a vehicle, a hollow frame located beneath said boom member and including front, rear and side sections, universal coupling means pivotally connecting said frame at said front section thereof to the forward end of said boom member, means between said rear section of said frame and said boom member for limiting downward movement of said frame, a plurality of arms extending longitudinally of said frame beneath the latter, said arms being spaced transversely of said frame, each of said arms being independently pivotally connected at the forward end thereof to said front section of said frame, and a plurality of independently suspended mine exploding wheels spaced transversely of said frame, each of said wheels being independently and rotatably mounted in one of said arms rearwardly of the pivotal connection of said arm to said frame.

2. The mine exploder of claim 1, wherein said boom member comprises a pair of boom arms converging and joined by bracket means at their forward ends and adapted at their rearward portions for limited pivotal mounting to each side of the forward part of a vehicle.

3. The mine exploder of claim 1, wherein said means between said rear section of said frame and said boom member for limiting downward movement of said frame comprises a flexible cable having its opposite ends pivotally connected to said rear section of said frame and to said boom member, respectively.

4. A mine exploder comprising a boom member, means for pivotally mounting said boom member at a rearward portion thereof to a forward part of a vehicle, a frame located beneath said boom member, said frame including front, rear and side sections, means pivotally connecting said frame at a point on said front section

thereof to the forward end of said boom member, means between said rear section of said frame and said boom member for limiting downward movement of said frame, a plurality of arms extending longitudinally of said frame beneath the latter, said arms being spaced transversely of said frame, each of said arms being independently pivotally connected at the forward end thereof through a resilient torsion bushing to said front section of said frame, and a plurality of independently suspended ground engaging wheels spaced transversely of said frame, each of said wheels being independently and rotatably mounted in one of said arms rearwardly of the pivotal connection of said arm to said frame.

5. A mine exploder comprising a boom member, means for pivotally mounting said boom member at a rearward portion thereof to a forward part of a vehicle, a frame located beneath said boom member, said frame including front, rear and side sections, means universally connecting said frame at a point on said front section thereof to the forward end of said boom member, means between said rear section of said frame and said boom member for limiting downward movement of said frame, a plurality of arms extending longitudinally of said frame beneath the latter, said arms being spaced transversely of said frame, means for inde-

pendently pivotally connecting each of said arms at the forward end thereof through a resilient torsion bushing to said front section of said frame, a plurality of independently suspended ground engaging wheels spaced transversely of said frame, each of said wheels being independently and rotatably mounted in one of said arms rearwardly of the pivotal connection of said arm to said frame, and means carried by

10 said frame cooperating with the rearward ends of said arms to limit upward movement thereof.

6. The mine exploder of claim 5 in which said means cooperating with the rearward ends of

15 said arms comprises a resilient pad carried by

said rear section of said frame.
